UNITED STATES PATENT OFFICE.

SAMUEL KORF, OF NEW YORK, N. Y.

POCKET ARTICLE-GUARD.

No. 867,051.

Specification of Letters Patent.

Patented Sept. 24, 1907.

Application filed June 25, 1904. Serial No. 214,183. (Model.)

To all whom it may concern:

Be it known that I, SAMUEL KORF, a citizen of the United States, residing in the borough of Brooklyn, county of Kings, city and State of New York, have invented a certain new and useful Improvement in Pocket Article-Guards, of which the following is a specification.

This invention relates to an apparatus designed to prevent the surreptitious abstraction and the pulling 10 of articles from pockets and similar receptacles wherein the articles are contained. These objects are attained by the mechanism or apparatus illustrated in the accompanying drawing, in which

Figure 1 is a view in perspective of one side of the apparatus; Fig. 2 is a view in perspective of another side of the same apparatus; Fig. 3 is a view of a vertical section of the same apparatus as shown in Fig. 1, except that in Fig. 3 the rod A has been lifted and the catches BB have thereby been caused to project from 20 the sides of the apparatus; Fig. 4 is a view from below of a horizontal section of the same apparatus along the line XX in Fig. 3, showing the catches BB projecting from the sides of the apparatus as in Fig. 3.

In the several figures mentioned, A is a rod at one 25 end of which one or more catches BB are secured in such manner that when the rod A is pulled from its normal position, as shown in Figs. 1 and 2, the exterior arms of the catches BB will project downward and outward from the sides of the apparatus as shown 30 in Fig. 3.

In the special form of the apparatus shown in the figures of the drawings, and especially in Fig. 3, the rod A is provided at its lower end with a slot or opening C. Across the slot or opening C a pin D runs, and 35 upon the pin D the catches BB are pivoted. The catches BB, pivoted as aforesaid upon the pin D, turn also upon the edges EE of the piece F when a pull is exerted upon the rod A. The catches BB are bent as shown in Fig. 3 at the places where they turn 40 upon the edges EE, and as a consequence when a pull is exerted upon the rod A, the exterior arms of the catches BB project downward and outward from the sides of the apparatus. The openings near the lower end of the body F through which the catches BB extend, are, as shown in Fig. 3, of such narrow width or extent, that, at the points where the catches extend through the openings, one side of the catch is near to the edge E about which the catch bends and turns, while the other or opposite side of the catch is near to 45 the side of the opening opposite the edge E; so that when a pull is exerted upon the rod A and the rod A rises, one side of the catch will at once come into contact with the edge E and the exterior arm of the catch will be forced to project downward and outward from 50 the outer surface of the body F. When the rod A is

forced downward the catches BB again turn about the edges EE about which they bend and near to which they always are, as shown in Fig. 3, because of the narrowness of the openings through which the catches extend, and the several parts of the device resume their 60 normal positions.

The rod A is provided with a spring G, shown in Fig. 3, so arranged that when no pull is exerted upon the rod A, the pressure of the spring G will cause the rod A to push upon the catches BB pivoted on the pin D, and thereby bring the points of the catches BB close to the sides of the apparatus, as shown in Figs. 1 and 2. As shown in Fig. 3 the catches BB pass through openings at EE near the lower end of the swivel, the rod A passes through a bore or cavity extending centrally 70 through the length of the swivel, and the sides of the lower part of the rod A contact with or lie close to the walls of the central bore or cavity. The edges HH, which are exterior to and surround the body F at its lower end assist in bringing and keeping the catches BB 75 close to the sides of the apparatus while the spring G holds the rod A in its normal position, shown in Figs. 1 and 2. When the pressure of the spring G causes the rod A to push upon the catches BB, any resisting piece such as the edges HH against which the catches BB 80 are pressed will cause the arms of the catches which are exterior to the watch-swivel or piece F to be brought and held close to the outer surface of the swivel. Recesses may be formed in the sides of the piece F to receive the catches BB, and to prevent the points of the 85 catches BB from projecting when the rod A is held in its normal position by the spring in the absence of any pull exerted upon the rod A. In Figs. 1 and 2, the catches BB are represented in such recesses upon the sides of the piece F.

In Figs. 1, 2 and 3, K is a hook or other suitable means by which to secure an article, such as a watch, coin, ring or other object to the apparatus above described.

In Figs. 1, 2 and 3 L is a ring or other suitable means by which to attach a chain, cord, thread or other means 95 of holding and securing the watch or other article to which the apparatus above described is attached.

When a pull is exerted upon the rod A, the catches BB will, as above explained, project from the sides of the apparatus, and the points of the catches BB will 100 catch upon the sides of cloth or of other material of the pocket or other receptacle in which the pocket-article-guard to which a watch or other article is secured may be.

In order to take from the pocket a watch or other article secured to a pocket-article-guard made according to my invention, it is withdrawn from the pocket not by pulling upon the chain or other means of holding and securing it, but by taking hold of the pocket-article-guard.

The special form of the apparatus or pocket-article-guard shown in the figures of the drawings is a watch-swivel embodying my invention.

Heretofore in the manufacture of safety-guards for 5 watches, spurs or prongs have been concealed within the barrel or case of a watch-swivel and have been so arranged that when a pull was exerted upon the watch chain they would project through openings or slots situated at the top or the upper part of the swivel. According 10 to my invention, the catches BB are placed on the outside of the pocket-article-guard, and hinge or turn at the lower end of the guard, and this arrangement, according to my invention, insures the contact of the catches BB with the sides of cloth or of other material 15 of the pocket before the article to which the pocket-article-guard may be secured has been withdrawn from the pocket.

What I claim is:

1. A guard for pocket articles having attaching means 20 at each end, a tubular part, a sliding rod mounted within said part and engaging one of said attaching means, a spring pressing against said rod and tubular part to hold the rod normally retracted in the tubular part, a catch arm pivoted to the rod within the guard and said arm having a part extending substantially horizontally from the pivot when the arm is in retracted position, said arm passing under the edge of the guard wall so as to have a fulcrum bearing thereon and having a straight piercing portion lying outside the wall and extending from the other portion substantially at a right angle thereto whereby the piercing portion will be projected outward at an acute angle to the tubular part upon a slight vertical movement of the rod-pivot, and said piercing portion will lie flat against the outside surface of the tubular part when in 35 retracted position, substantially as described.
2. A guard for pocket articles having attaching means at each end thereof, a tubular part and sliding rod mounted within said tubular part and engaging one of said attaching means, a spring pressing against said rod and 40 tubular part to hold the rod normally retracted in the tubular part, catch arms at the inner end of said rod mounted on a common pivot extending centrally across the tube, said arms each having a part extending substantially horizontally from the pivot when the arm is in retracted 45 position, and passing under the edge of the wall of the tubular part so as to have a fulcrum bearing thereon, and

having a straight piercing portion lying outside the wall and extending from the first portion substantially at a right angle thereto whereby the piercing portion will be projected outward at an acute angle to the tubular part 50 upon a slight vertical movement of the rod pivot and the said piercing portion will lie flat against the outside surface of the tubular part when in retracted position, substantially as described.

3. A guard for pocket articles having attaching means 55 at each end, a tubular part, a sliding spring-pressed rod within said part connected to one of said attaching means, angularly bent catch-arms pivoted to said rod at the inner part thereof and having portions which lie entirely outside of said tubular part, said tubular part being made 60 open at its inner end and said arms bearing against the edge of said open tubular part at the bend of said arms and one of said attaching means being secured directly to the edge of the open end of said tubular part, substantially as described.

4. A guard for pocket articles having an article attaching member at one end, a slide rod secured thereto, a tubular part in which said rod moves, a spring for holding said rod in retracted position, angularly bent arms pivoted centrally to the inner part of said rod and having 70 piercing portions lying outside of said tubular part, a hook secured to the inner end of said tubular part, a pivoted latch co-operating with said hook and having a tongue extending within the tube in position to be pressed upon by the catch arms when the latter are in retracted position, 75 substantially as described.

5. A guard for pocket-articles having attaching means at each end thereof and having an intermediate tubular part, a spring-pressed sliding rod within said tubular part and having at one end an outside portion adapted to be 80 secured to one of said attaching means, said rod having at its inner end an enlarged portion which closely fits the bore of the tube and having angularly bent arms centrally pivoted in said enlarged portion, said arms bearing against the edge of the tubular part at the bends of the 85 arms and having piercing portions which lie outside of the tube and are adapted to be projected outwardly and downwardly by pressure against the wall of the tube when the rod is pulled, substantially as described.

In testimony whereof I have signed my name to this 90 specification in the presence of two subscribing witnesses.
